 Filed Mar. 9, 1960, Ser. No. 13,824
 5 Claims. (Cl. 78—9)

This invention relates to an improved double blow header which is adapted to manufacture a general range of bushings and sleeves characterized by a large diameter hole in the center thereof.

An object of the present invention is to provide an improved double blow header especially adapted to manufacture bushings and sleeves having a large diameter hole in the center in a rapid, efficient, and economical manner.

A further object of the invention is to provide a punch and die assembly which may be used with a conventional double-blow header.

Other objects and advantages of the present invention will be apparent to those skilled in the art from the following detailed description and drawings in which like numerals relate to like parts and in which:

FIGURE 1 is a cross sectional view of a double blow header of the present invention in the first or initial position;

FIG. 2 is a view similar to FIG. 1 in the second position in which the article has been formed by the first punch blow;

FIG. 3 is an enlarged cross sectional view of the die assembly in the position of FIG. 2;

FIG. 4 is a cross sectional view taken along the lines 4—4 of FIG. 3 showing the ejector sleeve pin spacing arrangement;

FIG. 5 is a view partially in cross section showing the third or finishing blow position in which the large diameter hole is formed in the article and it is formed to final shape;

FIG. 6 is a view partially in cross section showing the finished article being ejected; and

FIG. 7 is a view partially in cross section similar to FIG. 6 showing the waste slug being ejected.

According to this invention, a slug of metal is cut off in the conventional manner and is positioned over the die tooling (FIG. 1), it is hit a forming blow by the first punch (FIGS. 2 and 3), the header slides to present the finishing punch to the die tooling and the article is hit a second or finishing blow by the finishing punch to form a large diameter hole in the center thereof (FIG. 5), the finished article or product (FIG. 6) is ejected, and lastly the slug formed by the material from the central hole is separately ejected (FIG. 7). The only material wasted in the whole operation is the slug formed in the finishing blow which provides the large diameter hole in the finished article.

A slug 1 normally of one to two diameters in length is cut off and transferred to a position in front of the die cavity as shown in FIG. 1. The ejector pin 6 is then flush with the face of the die cavity, having been retained there at the end of the previous stroke. The die itself is recessed within the die case 30 a distance slightly greater than the total length of the slug 1.

The coning or stover punch 3 then advances toward the die with the air or spring stover pin 2 extending a substantial distance out from it and, as soon as this pin has contacted the cut-off slug 1, it presses it against the ejector pin 6, thereby permitting the early retraction of the cut-off knife while the spring stover pin 2 remains pressed against the slug 1. The means for cutting off the slug 1 is a conventional cut-off knife and is not shown. The stover punch 3 continues to advance until it has caught up with the face of the air or spring pin 2 and then the

2

two, being flush, force the slug against the ejector pin 6 and into the die cavity. At this point the outside diameter of the stover punch 3 is piloted by the flared mouth and close fitting internal diameter of the collet 27 in 5 which the die itself is recessed, thereby establishing concentricity.

The coning punch has a shaped forming head 5 and a longitudinal bore 46 into which the spring stover pin 2 retracts at the bottom of the forming stroke. Spring 4 in the bore 46 keeps the spring stover pin in the work 10 engaging position shown in FIG. 1 until the punch bottoms on the work as shown in FIG. 2. The punch 3 reciprocates in a cylindrical guide hole 21 formed in the punch block 29.

As the punch advances further it forces the slug 1 against the ejector pin 6 within the die itself. While the ejector pin 6 was forward from the ejection of the previous product or piece, the sliding block or stop 10 was placed in position behind the ejector rod 8 at the back of the header so that the ejector pin 6 extends well up into the die cavity a sufficient distance to cause the slug to backward extrude down around the ejector pin 6. The center portion of the stover punch 3, including the pin 2, causes the center of the product 41 to be reduced to a relatively thin web portion 42 which is pierced or sheared out in the second blow. The web portion 42 is shown thicker than it usually is for purposes of illustration. In practice, it is made as thin as practicable.

Simultaneously with the completion of the extrusion backward around the ejector pin 6 into the bottom of the die, the stover punch 3 causes the top of the slug to upset or flare out radially to form the flange or top portion of the product 43 and, as the stover punch bottoms, the die is completely filled to within a few thousandths of final tolerance. This is shown in FIGS. 2 and 3.

During this process, the shoulder 22 on the ejector sleeve 7 has retracted into engagement with the die heel plate 24 so that there is some backward extrusion from the face of the ejector pin 6, the amount of backward extrusion being less than the final lengthwise dimension of the product 41. The internal diameter of the ejector sleeve 7 is substantially equal to the diameter of the hole through the product and is a slip-fit over the ejector pin 6. The face of the ejector pin 6 is preferably forward of the face of the ejector sleeve 7 by .020 to .100 of an inch, depending upon the particular product.

Next the stover punch 3 retracts and is replaced, by a shift of the slide, by the finishing punch 36. The finishing punch 36 has a short, bevelled cylindrical section 48 protruding from its face which is a few thousandths of an inch smaller than the internal diameter 49 of the collet 27 so that when the finishing punch comes forward, it is brought into perfect concentricity with the die case 30 and dies 33 and 34.

Having been brought into alignment by the internal diameter 49 of the collet 27 in the die, the finishing punch 36 now advances until its cylindrical nose 39 pierces the slug 40 out of the center of the product 41. This is possible because while the punch was shifting, the block 10 behind the ejector pin 6 and ejector rod 8 was withdrawn so that it is now free to travel backward as the slug is pushed out of the product 41. However, inasmuch as it stands up closely against the bottom of the slug, completing the backward extrusion, it is impossible for this part of the piece being made to collapse or mushroom.

As the cylindrical section 39 of the punch 36 emerges from the back side of the product 41, it forces the slug 40 into the ejector sleeve 7 which has also been allowed to recede because it was only being held forward by the shoulder 20 on the ejector rod 8.

As the finishing punch 36 bottoms, it reduces the

flange or top 43 of the product 41 to final dimensions and causes slight forward extrusion around the piercing punch down against the bottom of the sleeve 7 surrounding the ejector pin 6. However, this does not drive a burr out through the space between the punch section 39 and the ejector sleeve 7 because of the fact that there is a slight void caused by the ejector sleeve 7 having been held forward by the ejector rod 8 in the first blow into which the metal that is forward extruded during the final coining of the product can flow. This is shown in FIG. 5.

During the withdrawal stroke of the finishing punch, the ejector sleeve 7 is driven forward through the heavy Belleville springs 15 by the knockout bar 9 engaging the collar 12 on the ejector rod 8 so that the part 41 is driven out of the die without the ejector sleeve 7 or the slug 40 moving inside of the ejector sleeve 7 which contain them. This is shown in FIG. 6.

When the ejector sleeve 7 has traveled all the way forward against a stop and thereby completely ejected the finished piece from the die, the Belleville springs by which it is driven are compressed and the additional travel of the knockout bar causes the ejector pin 6 to advance once or twice the thickness of the slug further forward, thereby ejecting the slug 40. This is shown in FIG. 7.

The differential and sequential travel between the ejector pin 6 and ejector sleeve 7 is provided by the arrangement of the impact sleeve 12, collar 13 and Belleville springs 15.

The ejector pin 6 is attached to or integrally formed with the ejector rod 8 which is of a larger diameter than the ejector pin 6. The ejector rod 8 has a cap 11 at the back end thereof which rests against a back-up block 10 when the punch 3 bottoms on the work piece as shown in FIG. 2. Back-up block 10 slides in slot 31 in the feed roll and knockout mounting block 47. The ejector sleeve 7 fits loosely over the ejector pin 6 and is prevented from retracting in the positions of FIGS. 2-5 by shoulders 20 on the ejector rod 8 and cooperating flange portions 22 on the ejector pin 7 and die heel plate 24.

A collar 13 is attached to the ejector pin 8 in back of the die assembly by a retaining pin 14. Fitting over this collar is an impact sleeve or cap 12 which projects forward and around the collar and engages Belleville springs 15. A spring retaining sleeve 16 rests against the other end of the Belleville springs and a spacer sleeve 17 is provided to help adjust and position the Belleville springs. A series of spider pins 18 space the ejector sleeve 7 from the spacer sleeve 17 as desired, and accurately locate the ejector sleeve 7. The pins 18 are positioned in slots 23 formed in the die heel plate 24, this arrangement being shown in FIG. 4.

The ejector sleeve 7 is spaced from the impact sleeve 12 by the Belleville springs, retaining sleeve 16, spacer sleeve 17, and pins 18. When the impact sleeve 12 is first struck by the knockout bar 9, it is spaced from the collar 13 as shown in FIG. 2. It advances against the Belleville springs and the intermediate units to drive the ejector sleeve 7 forward. This ejects the finished article 41 as shown in FIG. 6. As the blow of the knockout bar progresses, it compresses the Belleville springs and ultimately seats on the collar 13. This ejects the slug 40 as shown in FIG. 7. The spacing between the collar 13 and impact sleeve 12 and compression of the Belleville springs thus provides sequential travel between the ejector sleeve and ejector pin. The knob 32 is provided on the knockout bar 9 to engage the collar 12. Regular coil springs or other spring means such as alternate layers of rubber and metal washers may be used instead of the Belleville springs.

The die assembly consists of a die block 25, a high tensile die case 30 positioned inside the die block, a die anvil 28 positioned between the die case 30 and the back-up block 24, a collet 27, a die shim 35 and inner and outer die members 33 and 34. Frame 26 of the header supports and backs up the die block 24.

The finishing or second punch is illustrated in FIG. 5. It comprises a stripper collar 37, a stripper spring 38 and a forming punch head piece 39. The purpose of the stripper assembly is to keep the finished piece 41 in the die as the punch withdraws and prevent it from retracting with the head piece 39.

The forming axis A—A is shown in FIG. 1. It should be noted that this is the axis common to the ejector rod, ejector pin, ejector sleeve, and die tooling. It is also the axis in which the storer and finishing punches reciprocate when in the operating position.

The block 10 against which the ejector rod 8 bottoms in normal operation is caused to move in and out of position every other stroke by suitable actuating means, such as a cam or small air cylinder. The timing of the placement and removal of this block is not critical. Its travel takes place between strokes and at no time is it caused to move when it is under load. To further illustrate, it is placed behind the ejector bar, or rod when it is in the full forward position and is removed from behind it after the part has bottomed against it.

The modified double header of the present invention permits very economical production of high quality valve spring caps, lock bolt collars, flanged bushings and similar parts. It is suitable for high volume production of either straight or tapered holes, cylindrical, hexagonal, or other shapes, in alloys capable of being cold-headed.

What I claim is:

1. In combination, a frame, a die assembly and an ejector rod mounted on the frame, and punch means adapted to sequentially engage work-pieces in said die assembly, an ejector pin on the die assembly end of the ejector rod with a smaller diameter than the ejector rod, an ejector sleeve fitting over said ejector pin with a slip-fit, a back-up block adapted to engage and disengage the other end of said ejector rod, a collar on the ejector rod between the ejector sleeve and back-up end of said ejector rod, a cap fitting over said collar with portions projecting forward therefrom toward the die assembly, a knock-out bar adapted to strike said cap, spring means on said ejector rod which engage said cap and are located between said cap and the die assembly, and means spacing the forward end of said spring means from said ejector sleeve and being reciprocable along the axis of the ejector rod, said cap being spaced from said collar by said spring means in the normal position and being adapted to engage said collar only at the end of the stroke of the knock-out bar.

2. The apparatus of claim 1 in which the spring means comprises Belleville springs.

3. The apparatus of claim 1 in which the spring means comprises Belleville springs and the spacing means comprises a sleeve slidably mounted on the ejector rod and at least two spider pins connecting said sleeve to the ejector sleeve.

4. In combination, a frame, a die assembly and an ejector rod mounted on the frame, and punch means adapted to sequentially engage work-pieces in said die assembly, the improvement which comprises an ejector pin on the die assembly end of the ejector rod with a smaller diameter than the ejector rod, an ejector sleeve which fits over said ejector pin with a slip-fit and has a smaller internal diameter than the diameter of the ejector rod so as to abut against it in a bottoming position, a block adapted to engage and disengage the other end of said ejector rod so as to positively restrain its backward movement, a collar disposed on the ejector rod between the ejector sleeve and back-up end of said ejector rod, a cap fitting over said collar with portions projecting forward therefrom toward the die assembly, a knock-out bar adapted to strike said cap, spring means on said ejector rod which engage said cap and are located between said cap and the die assembly, and means separate from said ejector sleeve which provides a positive driving connection between it and said

70
75

spring means, said ejector rod, ejector pin, and ejector sleeve having a common axis.

5. In combination, an ejector rod, an ejector pin on the end of the rod with a smaller diameter than the rod, an ejector sleeve slidably mounted on said ejector pin and having a smaller internal diameter than the diameter of the ejector rod, a block for engaging and disengaging the other end of said ejector rod to restrain its backward movement, a collar disposed on the ejector rod between the ejector sleeve and the end of said ejector rod, a cap fitting over said collar with portions projecting forward therefrom, a knock-out bar for striking said cap, spring means on said ejector rod for engaging said cap, and

means providing a positive driving connection between the ejector sleeve and said spring means, said ejector rod, ejector pin, and ejector sleeve having a common axis.
